UNITED STATES PATENT OFFICE.

EMIL R. MEYER, OF BROOKLYN, NEW YORK.

PHONOGRAPH-RECORD CABINET.

1,366,203.

Specification of Letters Patent. Patented Jan. 18, 1921.

Application filed July 22, 1920. Serial No. 398,128.

To all whom it may concern:

Be it known that I, EMIL R. MEYER, a citizen of the United States, residing at the borough of Brooklyn, county of Kings, city 5 and State of New York, have invented an Improvement in Phonograph-Record Cabinets, of which the following is a specification.

My invention relates to devices for holding record-disks for the reproduction of articulate speech or airs for mechanical musical instruments.

Devices heretofore employed for this purpose usually consist of a case or cabinet provided with a plurality of either vertically or horizontally spaced partitions made of wood or metal between or upon which the disks are placed or laid. These partitions present a hard surface in contact with the 20 records which is liable to injure the same; furthermore such partitions are expensive, and unless made of comparatively thick wood, are easily cracked or broken, and if made of thick material, considerable space 25 is occupied by the partitions, thereby limiting the holding capacity of the cabinet.

The principal object of my present invention is to provide a holder for record-disks, in which both sides of the disks are 30 protected by a soft flexible support, thereby avoiding any possibility of injury to the records while contained in the cabinet, while at the same time permitting a greater number of disks to be held in one cabinet than 35 in those of the same size heretofore constructed, thereby economizing in space, labor and expense; its further advantages over the prior art will be recognized by the following description in which the details 40 of the invention are more fully set forth.

In the accompanying drawings:

Figure 1 is a front elevation of my improved cabinet, partially in section.

Fig. 2 is a sectional view on the broken line 2-2 of Fig. 1.

Fig. 3 is a sectional plan view on the broken lines 3-3, of Fig. 1.

Fig. 4 is a detail view of the cord loop, and

Fig. 5 is a fragmental view illustrating a modified manner of fastening the ends of the cords.

Similar reference characters indicate like parts throughout the several views.

10 indicates a rectangular casing or cabinet, open at the front, and provided with a

door 11, for closing such opening, which door is connected to one of the side walls 12, by hinges 13. This door may be held closed by any suitable lock or catch, such as the 60 hook 14, and pin or screw 15.

Upon the inner surface of the bottom of the cabinet and at a predetermined distance from its front opening, I provide a transverse strip 16, of wood or other suitable material, which is fixed to the bottom of the cabinet by any suitable means, preferably by screws 17. The upper surface of this strip 16 is inclined rearwardly as at 18, while its front is under-cut, leaving a lip or 65 projection 19, which extends longitudinally of the strip its entire length. This lip or projection is provided with a plurality of 70 vertical slots 20, open at the front, top and bottom, and spaced the entire length of the 75 strip.

21 denotes another transverse strip, similar to the strip 16, and provided with similar vertical slots 22 in its front projection 23; this strip is secured to the inner surface 80 of the top 24 of the casing 10 by screws 25, or other suitable means, and is in direct alinement with the lower strip 16.

Upon the inner surface of the bottom of the casing to the rear of the strip 16, I 85 place a piece of felt 26, or other suitable material, which extends to a predetermined distance from the rear wall of the casing, and is secured to the bottom thereof by glue 90 or other suitable means.

27 indicates another strip of felt or similar material, which is secured in a similar manner to the inner surface of the top of the casing at the rear of the strip 21.

28 denotes a strip of wood or other suitable material which extends transversely in the casing, at or near the rear thereof, and at a predetermined distance from the bottom. This strip 28 is secured to the casing by any suitable means, preferably by screws 95 100 29, passing through the side walls of the casing. The front surface of this strip 28 is inclined downwardly a certain distance and then inwardly a certain distance, its bottom edge being straight and provided with 105 spaced transverse grooves 30, its entire length.

31 denotes another transverse strip of like formation to the strip 28, and secured to the casing in the same manner, but at a predetermined distance from the top, in direct alinement 110 with the strip 28. This strip 31 is

positioned reversely of the strip 28, so that the transverse grooves 32 therein are at the top of the strip.

33 indicates a cord, one end of which is secured to the inside of the casing or to the strip 16 in any suitable manner; I have shown it provided with a knot 34, taking against the under surface of the strip 16, the cord being inserted in the end slot in said strip. This cord is then drawn into the alined slot in the upper strip 21, across the top of the said strip 21, then into the next slot in said strip and downwardly into the second slot in the strip 16, then upwardly through the next alined slot in the respective strips 16 and 21, and so on the entire length of said strips, the other end of the cord 33 being secured by the knot 35, or in any other suitable way.

36 denotes a series of loops, which are preferably formed of a strip of fabric, the ends of which are folded over and joined in the center of the loop by a vertical line of stitching 37, as most clearly shown in Fig. 4 of the drawing.

In positioning the cord 33, in the manner above described, its free end is passed through the loops 36, at each upward and downward movement between the alined slots 20 and 22 in the strips 16 and 21, so that they assume the position most clearly shown in Fig. 1.

After the cord or cords 33 have been thus positioned, I place a transverse block or strip 38 in front of and bearing against the face of the strip 21. I also place another transverse block 39 in a similar manner in front of the strip 16. These blocks or strips 38 and 39 are secured to the casing in any suitable manner, preferably by screws 40 and 41, and effectually prevent any possibility of the cord 33 working out of the slots in the respective strips 16 and 21.

42 indicates a plurality of cords, corresponding in number with the loops 36. Each of these cords 42 is passed through a loop 36, and the ends are drawn into the grooves 30 and 32, in the respective rear strips 28 and 31, a knot 43 being made in each end of the cords to bear against the rear surface of the respective strips. These cords may be secured against working out of the grooves in any suitable manner.

I prefer to employ transverse cleats 44, which are secured to the casing in any suitable manner, preferably by screws 45, passing through the side walls 12. These cleats are applied after the cords 42 have been drawn into the grooves 30 and 32, and prevent any possibility of the cords working out of the grooves. In addition to these cleats, or without their employment, the ends of each cord 42 may be held by a tack or nail 46, as illustrated in Fig. 5. It will be noticed that that portion of the cords 42, adja-

cent their ends, bear against the inclined surface of the strips 28 and 31, so that there is no sharp contact which might tend to cut or injure the cords.

Both the cord or cords 33, and the cords 42, are drawn sufficiently taut to prevent undue lateral movement of the same. This arrangement provides vertical spaces 47 between the cords, into which the record-disks 48 are placed, being of course inserted at the open front of the casing.

To facilitate the insertion of the record-disks, the upper surface of the block 39 is inclined downwardly from front to rear and provided with transverse grooves 49 which register with the spaces between the vertical cords. This inclined surface also retards the record-disks rolling out the front opening, should the casing be accidentally tipped forward.

The cords 33 and 42 provide a soft flexible support at both sides of the record-disks, and are sufficiently thick to avoid any possibility of one record touching another record at any point while in the cabinet. The vertical cords 33 bear against the forward side portions of the record, while the divergent cords 42 bear against the center and rear portions of the sides of the records. The bottom edges of the records normally rest upon the felt lining 26. Should the casing be tipped to a sufficient degree, the edges of the record disks would contact with the upper strip of felt 27, by which injury to the records would be prevented.

The front inclined surfaces of the rear strips 28 and 31 prevent the edges of the records contacting with the rear wall of the casing. It is obvious that the faces of these strips might be covered with felt or other soft material if desired.

I prefer that the front vertical surface of the block 39 be marked in a manner to indicate certain classes of music or composers. This may be done by dividing the front into sections of different colors, which may be painted directly upon the block, as indicated at *a*, *b*, *c*, *d*, *e*, in Fig. 1, or such colors or names may be upon a separate strip, as at 50 (Fig. 1) attached to the front of the block 39 in any suitable manner.

It will be understood that my improved record holding device may be built up in the same cabinet containing the musical instrument with which the records are to be used, or it may be a separate cabinet or casing, as shown in the drawing, in which case it is adapted to be placed within a cabinet containing the musical instrument when desired. When made for use, apart from the instrument cabinet, it may be of any desired exterior design or ornamentation.

It is obvious that instead of employing a single length of cord to form the vertical series 33, separate lengths of cord may be

used, knotted at their ends below and above the slots in the strips 16 and 21, but I prefer to employ a single length of cord in order to save labor.

5 By the employment of my invention, any possibility of injury to the record disks while in the cabinet is prevented; a greater number of disks can be contained in one cabinet of a certain size than heretofore, 10 while space, labor and expense is economized.

I claim as my invention.

1. A holder for record disks comprising a casing open at one side, a plurality of vertically spaced cords within the casing and connected thereto adjacent said opening, and other cords connected with said vertical cords and extending rearwardly therefrom forming a plurality of receptacles for the 20 disks.

2. A holder for record disks comprising a casing open at one side, a strip secured to the bottom of the casing and extending transversely thereof and provided with a 25 plurality of open slots in its forward edge, another transverse strip secured to the inner upper surface of the casing in alinement with said lower strip and also provided with open vertical slots in its forward edge, two 30 spaced transverse strips secured within the casing adjacent its rear wall and each provided with transverse grooves, a plurality of vertical spaced cords inserted within the slots in the two front transverse strips, a 35 plurality of loops through which said vertical cords pass, other cords passed through said loops at the rear of said vertical cords with their ends drawn into the grooves in said two rear strips, and means for securing 40 them therein.

3. A holder for record disks comprising a casing open at one side, a strip secured to the bottom of the casing and extending transversely thereof and provided with a 45 plurality of open slots in its forward edge, another transverse strip secured to the inner upper surface of the casing in alinement with said lower strip and also provided with open vertical slots in its forward edge, two 50 spaced transverse strips secured within the casing adjacent its rear wall and each provided with transverse grooves, a plurality of vertical spaced cords inserted within the

slots in the two front transverse strips, a transverse block bearing against the open 55 front ends of the slots in said front lower strip and secured to the casing, another transverse block bearing against the front open ends of the slots in said top transverse strip and secured to the casing, a plurality 60 of loops through which said vertical cords pass, other cords passed through said loops at the rear of said vertical cords with their ends drawn into the grooves in said two rear strips, and cleats secured to the casing and 65 bearing upon said cords for retaining them within the grooves.

4. A holder for record disks, comprising a casing, a series of spaced vertical cords adjacent the forward end and within said casing, means for holding the ends of said cords, a plurality of flexible loops engaging 70 said vertical cords at or about their centers, other cords engaging said loops at the rear of said vertical cords and extending rearwardly in the same plane, and means for 75 holding their ends.

5. A holder for record disks, comprising a rectangular casing having an open front, a transverse block secured to the inner surface 80 of the bottom of the casing at a predetermined distance from said opening and having an inwardly inclined rear surface, its front being undercut and provided with spaced slots open at the front, top, and bottom, another block of similar shape and provided with like slots secured to the inner top surface of the casing in alinement with said lower block, a plurality of cords with their ends passed into slots in the respective 85 blocks having their projecting ends knotted, a block secured to the bottom of the casing and bearing against the front ends of the slots in said first named block and having 90 its top inclined from front to rear and provided with transverse grooves registering with the spaces between said vertical cords, a plurality of flexible loops engaging said 95 vertical cords at or about their center, other cords engaging said loops at the rear of said vertical cords and diverging inwardly therefrom in the same vertical plane, and means 100 for holding their ends.

Signed by me this 17th day of July, 1920.

EMIL R. MEYER.
